UNITED STATES PATENT OFFICE.

JAMES A. SMITH, OF FATE, TEXAS.

COLLAPSIBLE BOX.

1,136,179.

Specification of Letters Patent.

Patented Apr. 20, 1915.

Application filed April 15, 1914. Serial No. 832,037.

To all whom it may concern:

Be it known that I, JAMES A. SMITH, a citizen of the United States, residing at Fate, in the county of Rockwall and State 5 of Texas, have invented certain new and useful Improvements in Collapsible Boxes, of which the following is a specification.

My invention relates to new and useful improvements in boxes and resides in the 10 provision of an extremely useful and inexpensive box that is particularly designed for shipping and storing eggs, fruits, and other fragile goods, and may be readily folded when not in use so as to take up little 15 room.

An important object of my invention is to provide a collapsible box of the character described which consists of hinged side and end walls and removable bottom and partition walls serving to hold the side and end 20 walls in extended and operative position.

Another important object of my invention is to provide novel means for hingedly securing the side and end walls to each 25 other, said means being simple as to construction and not liable to accidental derangement.

Another object of importance is to provide a collapsible box of the character described that is simple as to construction, reliable and efficient in operation and inexpensive to manufacture.

The above and additional objects are accomplished by such means as are illustrated 35 in the accompanying drawings, described in the following specification and then more particularly pointed out as claimed.

With reference to the drawings, wherein I have illustrated the preferred embodiment 40 of my invention as it is reduced to practice, and throughout the several views of which similar reference numerals designate corresponding parts, Figure 1 is a side elevation of my improved box, Fig. 2 is a transverse 45 sectional view taken on line 2—2 of Fig. 1, Fig. 3 is a side elevation of the box frame as it would appear when in folded position, Fig. 4 is a top plan view of the partition wall, and Fig. 5 is a detail view showing one 50 of the hinges which I employ.

Referring to the drawings by characters of reference, the numeral 1 designates as an 55 entire a box frame which consists of side walls 2 and 3 and end walls 4. A bottom wall 5 is designed to coöperate with the end and side walls and a lid or cover 6 is pro-

vided to rest upon the upper edges of the side and end walls. A horizontal partition wall 7 is arranged within the box and supported upon transverse supporting strips 8 60 that are secured by suitable fastening means upon the inner faces of the end walls. It is to be understood that any number of these partition walls 7 may be provided. The end walls 4 and side walls 2 and 3 comprising 65 the box frame 1 are hingedly connected with each other. Openings 9 are formed adjacent the corners of the side walls 2 and 3 and are arranged to coöperate with openings 10 formed adjacent the corners of the 70 end walls 4. At each end of the side walls, a vertical, preferably stiff wire 11 is secured. The wires 11 adjacent their ends are bent over the upper and lower edges of the side walls and inserted through the openings 9 from the inside of the walls and then bent to lie flat against the outer faces of the side walls as at 12 adjacent the openings 9 therein. It will be seen that the wires 11 75 are secured so as to be positioned in front of the openings 9. To hingedly secure the end walls 4 to the side walls I provide suitable wire strips 13 that are inserted through the openings 10 and have their free ends extending through the openings 9. The free 80 ends of the strips 13 are twisted as at 14 so as to surround the wires 11. It will be readily seen that the strips 13 in being arranged as described provide for the hinging of the side walls 2 and 3 with the end walls 4 thus 85 enabling the collapsing of the box frame 1 so that the frame will assume the position as shown in Fig. 3. The end walls are provided with longitudinal reinforcing strips 15 secured upon the inner faces of the end 90 walls adjacent the end edges thereof. The strips 13 surround the reinforcing strips 15. Secured upon the lower edges of the end walls 4 are transverse supporting strips 16 95 that are mounted upon the inner faces of the end walls and engage the end edges of the bottom wall 5 so as to support the same.

In assembling the box, the bottom wall is put into place from the top of the box frame so as to rest upon the supporting strips 16 100 and the partition wall 7 is then in the same manner placed within the frame so as to rest upon the supporting strips 8. The lid 6 may be secured in any suitable manner upon the top edges of the side and end 105 walls. The partition and bottom walls serve to hold the receptacle rigidly in open

position and it is only necessary to remove the partition and bottom walls to facilitate the collapsing or folding of the box as shown in Fig. 3. When the box frame 1 has been folded as shown in Fig. 3 in the drawings the lid, partition and bottom walls may be laid flat upon the folded frame and secured thereto in any suitable manner not shown.

10 It will be readily seen with reference to the foregoing description and accompanying drawings that I have provided a simple and inexpensive box that is particularly desirous for shipping eggs, fruit and the like, 15 may be readily folded so as to take up little room when not in use, is simple as to construction and cheap to manufacture.

10 In practice, I have found that the form 20 of my invention, illustrated in the drawings and referred to in the above description, as the preferred embodiment, is the most efficient and practical; yet realizing that the 25 conditions concurrent with the adoption of my device will necessarily vary, I desire to emphasize the fact that various minor 30 changes in details of construction, proportion and arrangement of parts may be resorted to, when required, without sacrificing any of the advantages of my invention, as set forth.

What is claimed is:—

1. A collapsible box comprising side walls, end walls hingedly connected with the side walls, said end and side walls having openings formed adjacent the corners thereof, wires mounted upon the outer faces of the side walls and extending in front of said openings therein, and wires inserted through the openings in the end walls and having 40 their ends twisted so as to surround the first named wires.

2. A collapsible box comprising side walls, end walls hingedly connected with the side walls, said end and side walls having openings formed adjacent the corners thereof, wires mounted upon the outer faces of the side walls and extending in front of said 45

openings therein, wires inserted through the openings in the end walls and having their ends twisted so as to surround the first 50 named wires and a removable bottom wall mounted within the side and end walls, a partition wall, and means to support the bottom and partition walls carried by the end walls.

3. A collapsible box comprising side walls, end walls hingedly connected with the side walls, said end and side walls having openings formed therethrough adjacent the corners thereof, wires mounted upon the outer faces of the side walls at the ends thereof and extending in front of the openings therein, wire loops mounted within the openings in the end walls and extending into the side wall openings and surrounding said 65 wires, vertical strips secured at the end edges of the end walls upon the inner faces thereof, said loops surrounding said strips, a bottom wall, and a lid.

4. A collapsible box comprising side walls, 70 end walls hingedly connected with the side walls, said end and side walls having openings formed therethrough adjacent the corners thereof, wires mounted upon the outer faces of the side walls at the ends thereof 75 and extending in front of the openings therein, wire loops mounted within the openings in the end walls and extending into the side wall openings and surrounding said wires, vertical strips secured at the end 80 edges of the end walls upon the inner faces thereof, said loops surrounding said strips, a removable bottom wall, transverse strips secured upon the inner face of each end wall, certain of said strips supporting said 85 bottom wall and a horizontal partition wall mounted upon the other of said strips.

In testimony whereof I affix my signature in presence of two witnesses.

JAMES A. SMITH.
